UNITED STATES PATENT OFFICE.

LEIF ERICKSEN, OF BROOKLYN, NEW YORK, ASSIGNOR TO SIDNEY M. HARRINGTON, OF BROOKLYN, NEW YORK.

DESIGN FOR A VENDING-MACHINE CASING.

49,055.

Specification for Design.

Patented May 16, 1916.

Application filed November 19, 1915. Serial No. 62,431. Term of patent 7 years.

To all whom it may concern:

Be it known that I, LEIF ERICKSEN, a subject of the King of Norway, residing in the borough of Brooklyn, county of Kings, and State of New York, have invented a new, original, and ornamental Design for Vending-Machine Casings, of which the following is a specification, reference being had to the two views shown in the accompanying drawing, forming part thereof, wherein—

Figure 1 is a side elevation of a vending-machine casing, showing my new design; and Fig. 2 is a partial plan.

I claim:

The ornamental design for a vending-machine casing, as shown.

LEIF ERICKSEN.
